EXPANSIBLE WINDER SHAFT

Edward H. Tidland, Camas, Wash.

Application July 26, 1949, Serial No. 106,869

5 Claims. (Cl. 242—72)

1

This invention relates to shafts and the like on which rolls of paper or other flexible webs are to be wound or from which they are to be unwound.

In particular, this invention relates to expandable shafts on which rolls of paper may be wound in a paper mill as the paper is produced, and from the cores of the finished rolls of which the shafts can be then withdrawn; and this invention relates similarly to expandable shafts which may be inserted in rolls of paper in order to support the rolls during the unwinding of the same.

An object of this invention is to provide an improved winder shaft or core shaft on which the paper or web can be wound directly and which can quickly and easily be withdrawn from the core of the wound roll.

Another object of this invention is to provide an improved expandable winder shaft which can be pneumatically expanded and which can be quickly contracted by permitting deflation to occur.

A further object of this invention is to provide an improved expandable shaft of simplified construction in which no collars, set screws, cones, expanding chucks, or other mechanical adjustments or similar adjusting elements will be required.

Since large size rolls in which paper may be wound, or from which paper may be unwound, often involve considerable weight, a common difficulty with many expandable shafts is that they are subject to substantial deflection when used with large or heavy rolls or when used under conditions of high speed.

An additional but important object of the present invention accordingly is to provide an improved expandable shaft which will have maximum strength in proportion to its size and weight.

A still further object is to provide a pneumatic expandable shaft in which a minimum amount of air pressure will be required for expanding the shaft and holding it in expanded position with a tight grip on the surrounding roll core.

Another object is to provide a simple and practical expandable shaft in which a smooth cylindrical metal outer surface will be presented to the surrounding paper core when the shaft is contracted.

The manner in which these objects and other advantages are attained will be explained in the course of the following brief description with reference to the accompanying drawings, in which drawings:

2

Figs. 1A, 1B and 1C are successive partial elevations of my improved expandable shaft, showing the same in expanded position, but with the roll of paper omitted therefrom for the sake of clarity, and with portions of the shaft shown broken away and in section, also for the sake of clarity;

Fig. 2 is a transverse section taken on line 2—2 of Fig. 1B but drawn to a larger scale, showing the shaft in expanded position;

Fig. 3 is a corresponding transverse section showing the shaft in contracted position;

Fig. 4 is a fragmentary section corresponding to line 4—4 of Fig. 1B, but showing the shaft in contracted position, this figure being drawn to the same scale as Figs. 2 and 3 and illustrating more clearly one of the spring elements by which the longitudinal, radially-movable segments are caused to return to their normal contracted position whenever deflation of the inner rubber tube permits; and

Fig. 5 is a perspective view of a portion of one of the radially-movable segments which extend longitudinally within the main body member of the shaft.

Referring first to Fig. 1, the main body 10 of my expandable shaft comprises a cylindrical tube of steel or other suitable metal, the outside diameter of which corresponds to the maximum diameter desired for the shaft when the shaft is in contracted position. The length of this cylindrical tube of the main body member is made approximately equal to the contemplated width of the rolls of paper to be wound upon, or unwound from, the expandable shaft.

Journals 11 and 12 form the ends of the shaft. One of these journals, thus the journal 11 as shown in Fig. 1, has a central channel 13 extending through it. The other journal 12 preferably comprises a solid shaft portion. The inner ends of these journals have their exterior diameters corresponding to the interior diameter of the tubular main body 10 of the expandable shaft and have a shrink fit with the ends of the main body 10 and are also secured therein by suitable set screws such as the set screw 14, shown by way of illustration. The exterior portions of the journals 11 and 12 are capable of being machined to suit the mountings in which the ends of the expandable shaft are to be removably supported for the winding or unwinding operation. The size of the journals, and similarly, the size of the main body of the expandable shaft, will of course depend upon the particular conditions

under which the expandible shaft is to be employed.

Within the main body 10 of the shaft, extending substantially the entire distance between the inner ends of the journal members, are a plurality of identical members 15 which I designate as longitudinal segments. In the particular shaft illustrated in the drawings there are three such longitudinal segments. The shape of these longitudinal segments will be clearly understood from Figs. 2-5 inclusive. Each segment has an outer curved surface, the radius of curvature of which corresponds approximately to the radius of the inside surface of the main member 10. Each segment 15 has a series of spaced, longitudinally-aligned ribs or raised portions 16 extending radially from the center line of the curved outer surface. The main member 10 is provided with longitudinally-aligned slots 17 corresponding approximately to the size of the ribs 16 and correspondingly placed, within which slots 17 the ribs 16 are slideable in and out in a radial direction. As apparent from Figs. 2 and 3, these ribs 16 extend radially from the curved outer surface of the segments 15 for a distance somewhat greater than the radial thickness of the main member 10. Thus when the segments 15 are caused to bear against the inside wall of the main member 10, as illustrated in Fig. 2, these ribs 16 will protrude beyond the outer surface of the main member 10 a short distance, and this short distance constitutes the radial extent of the effective expansion of the expandible shaft.

An inner tube 18 of rubber or similar resilient flexible material, extends through the interior of the flexible shaft and bears against the inside faces of the segments 15 at all times, and, when inflated, may also bear against portions of the inside face of the main member 10 between the segments 15. One end of the inner tube 18, thus the end 19 as shown in Fig. 1, is sealed. The other end 20 is connected to a small metal tube 21 extending through the channel 13 in the hub member 11. The tube 21 terminates at its outer end, and thus at the end of the shaft, in a suitable connection by means of which the outer end of the tube 21 may be connected to a source of air under pressure, and in the connection a suitable connection by means of which the outer end valve on ordinary automotive vehicle tires, through the medium of which air under pressure can be admitted into the tube 21 and thence to the inner tube 18, can then be held therein, and finally can also be quickly and easily released therefrom when desired.

When the inner tube 18 is inflated, the pressure of tube 18 against the segments 15 will press the segments 15 against the inside surface of the main member 10 causing the ribs 16 to protrude from the slots 17 on the outer surface of the main member 10 and to remain in such position as long as sufficient pressure continues in the inner tube 18. Under such condition the expandible shaft is maintained in its expanded condition illustrated in Figs. 1 and 2.

In order to cause the segments 15 to move inwardly quickly whenever the inner tube 18 is sufficiently deflated so that the ribs 16 will be withdrawn from the outer surface of the main member 10, as illustrated in Figs. 3 and 4, and in order to hold the segments 15 and ribs 16 in such inner position as long as the inner tube 18 remains deflated, I provide springs 23 (Figs. 1

and 4) at regularly spaced intervals along the main body member 10 in alignment with the ribs 16. These springs are mounted in internally-opening recesses or sockets 22. The sockets 22 have threads on their outer cylindrical walls which engage threads formed on the walls or threaded holes cut in the main member 10 thus enabling the spring-holding sockets 22 to be secured in place in the main member 10, as shown in Fig. 4. The inner ends of the springs 23 engage recesses 24 in the segments 15. The inner tube 18, even when deflated, prevents the segments 15 from being pushed too far inside the main member 10.

Actually, depending of course upon the size of the shaft, only a moderate amount of deflation of the inner tube 18 is required to cause the segments 15 with their ribs 16 to move from the extreme outer position of Fig. 2 to their withdrawn position of Fig. 3; and correspondingly only a comparatively small amount of air under pressure is required to bring the inner tube 18 from the partially deflated condition of Fig. 3 to the fully inflated condition of Fig. 2. Thus the effective expansion or contraction of the shaft is accomplished quickly and without excessive waste of air under pressure.

Since the main member 10 of my expandible shaft is tubular, with a maximum outside diameter, its strength will compare most favorably with its weight. Since the slots 17 for the ribs 16 are narrow and extend longitudinally they necessitate no serious weakening of the main member and thus of the shaft. When the shaft is in expanded position the segments 15, pressed against the inside wall of the main member 10 and bearing the ribs 16 on which the paper roll is supported, actually serve as reinforcement for the main member and consequently aid in resisting any tendency for the shaft to become deflected. Due to the maximum size and strength of the main member the junctions between the main member and the journal member at each end will also be of maximum strength for the size and weight of the shaft. Finally, the smooth cylindrical outer surface presented by the main member when the shaft is in contracted position facilitates the removal of the shaft from a roll at the completion of the winding or the insertion of the shaft into the core of a roll in preparation for the unwinding of the roll.

Some variations and modifications might of course be made in the expandible shaft which I have described and which I have shown in the drawings within the scope of my invention and without departing from the principle of the same. Thus the number of the segments 15 could be increased and the relative size of the parts and members could be varied depending upon the circumstances under which the shaft is to be employed and the nature of the paper or web for which the shaft is to be used. However, my shaft, constructed substantially in the manner illustrated, during an extensive testing period, has proven very successful in the accomplishment of the objects set forth in the beginning of this specification, and I regard the shaft as illustrated and described as the preferred form of carrying out the principle of my invention.

70 I claim:

1. In an expandible shaft of the character described, a main outside tubular member, a journal secured to and extending from each end of said main member, an interior channel extending 75 through one of said journals and leading into said

main member, a plurality of identical longitudinal segments mounted within said main member, each segment extending substantially the entire distance between said journals, spaced, longitudinally-aligned raised portions extending radially outwardly from said segments, holes in said main member for said raised portions permitting radial movement of said raised portions and therewith of said segments in said main member, the radial length of said raised portions being slightly greater than the radial thickness of said main member, the outer face of each segment comprising a curved surface of substantially the same radius of curvature as the interior of said main member, an inner tube of rubber located within said main member and extending over the inner faces of said segments, said inner tube having a tubular connection at one end extending through said journal channel, valve means at the outer end of said tubular connection for said inner tube permitting air under pressure to be delivered into said inner tube and held in said inner tube and released from said inner tube when desired, and spring means located within said main member causing said segments to be normally spaced from the inside wall of said main member when said inner tube is partly deflated, whereby inflation of said inner tube will cause the outer ends of said raised portions of said segments to protrude beyond the outside surface of said main member and thereby expand the effective size of said shaft.

2. An expandible shaft of the character described including a journal at each end of said shaft, a main integral outside hollow cylindrical main member extending the entire length of said shaft between said journal ends, a plurality of longitudinal segments mounted within said main member, each segment extending substantially the entire distance between said journal ends, spaced raised portions extending radially outwardly from said segments, holes in said main member for said raised portions permitting radial movement of said raised portions and therewith of said segments in said main member, the radial length of said raised portions being slightly greater than the radial thickness of said main member, an inner tube of flexible and resilient material located within said main member and extending over the inner faces of said segments, said inner tube having a tubular connection at one end extending through one of said journals, means at the outer end of said tubular connection for said inner tube permitting air under pressure to be delivered into said inner tube and held in said inner tube and released from said inner tube when desired, and spring means extending between said main member and said segments causing said segments to be normally spaced from the inside wall of said main member when said inner tube is partly deflated, sockets mounted in the wall of said main member and acting as mountings for said springs, whereby inflation of said inner tube will cause the outer ends of said raised portions of said segments to protrude beyond the outside surface of said main member and thereby expand the effective size of said shaft.

3. An expandible shaft comprising a main outside tubular member, a journal secured to and extending from each end of said main member, an interior axial channel extending through one of said journals and leading into said main member, a plurality of identical longitudinal segments mounted within said main member, each seg-

ment extending substantially the entire distance between said journals, spaced ribs extending radially outwardly from said segments, slots in said main member for said ribs permitting radial movement of said ribs and therewith of said segments in said main member, the radial length of said ribs being slightly greater than the radial thickness of said main member, the outer face of each segment comprising a curved surface of substantially the same radius of curvature as the interior of said main member, the ribs of each segment extending in longitudinal alignment along the center line of the outer face of each segment, an inner tube of rubber-like material located within said main member and extending over the inner faces of said segments, said inner tube having a tubular connection at one end extending through said journal channel, means at the outer end of said tubular connection for said inner tube permitting air under pressure to be delivered into said inner tube and held in said inner tube and released from said inner tube when desired, and springs extending between said main member and said segments causing said segments to be normally spaced from the inside wall of said main member when said inner tube is partly deflated, sockets having internally opening recesses mounted in the wall of said main member and acting as mountings for said springs, whereby inflation of said inner tube will cause the outer ends of said ribs of said segments to protrude beyond the outside surface of said main member and thereby expand the effective size of said shaft.

4. In an expandible shaft of the character described, a main outside tubular member, a journal secured to each end of said main member, a plurality of series of similar, longitudinally-aligned slots in said main member, the longitudinal spacing between the slots in each series considerably exceeding the longitudinal length of the individual slots, a plurality of rigid, longitudinal segments mounted within said main member for limited radial movement, each segment extending substantially the entire distance between said journals, spaced, longitudinally-aligned ribs extending radially outward from each segment corresponding to said slots, said ribs radially slidable in said slots, the radial length of said ribs being slightly greater than the radial thickness of said main member, an inner tube of flexible and resilient material located within said main member and extending over the inner faces of said segments, said inner tube having a tubular connection at one end extending through one of said journals, and valve means in said tubular connection permitting air under pressure to be delivered into said inner tube and held in said inner tube and released from said inner tube when desired, whereby inflation of said inner tube will force the outer ends of said ribs of said segments to protrude beyond the outer surface of said main member and thereby expand the effective size of said shaft, and whereby said segments will serve to reinforce said main member when said shaft is expanded.

5. In an expandible shaft of the character described, a main outside tubular member, a journal secured to each end of said main member, a plurality of series of similar, longitudinally-aligned slots in said main member, the longitudinal spacing between the slots in each series considerably exceeding the longitudinal length of the individual slots, a plurality of rigid,

longitudinal segments mounted within said main member for limited radial movement, each segment extending substantially the entire distance between said journals, spaced, longitudinally-aligned ribs extending radially outward from each segment corresponding to said slots, said ribs radially slid able in said slots, the radial length of said ribs being slightly greater than the radial thickness of said main member, an inner tube of flexible and resilient material located within said main member and extending over the inner faces of said segments, said inner tube having a tubular connection at one end extending through one of said journals, valve means in said tubular connection permitting air under pressure to be delivered into said inner tube and held in said inner tube and released from said inner tube when desired, and means connected with each of said segments within said

main member for moving said segments inwardly into normal position spaced from the inside wall of said main member whenever said inner tube is partly deflated, whereby inflation of said inner tube will force the outer ends of said ribs of said segments to protrude beyond the outer surface of said main member and thereby expand the effective size of said shaft, and whereby said segments will serve to reinforce said main member when said shaft is expanded.
